UNITED STATES PATENT OFFICE.

JAMES MCKECHNIE, OF BARROW-IN-FURNESS, ENGLAND, ASSIGNOR TO VICKERS
LIMITED, OF WESTMINSTER, LONDON, ENGLAND, A BRITISH COMPANY.

RECIPROCATING ENGINE.

Application filed July 7, 1922. Serial No. 573,438.

To all whom it may concern:

Be it known that I, JAMES MCKECHNIE, a subject of the King of Great Britain, residing at Naval Construction Works, Barrow-in-Furness, in the county of Lancaster, England, have invented certain new and useful Improvements in or Relating to Reciprocating Engines, of which the following is a specification.

10 This invention relates to reciprocating engines, such as internal combustion or steam engines, of the type employing a pair of cylinders each with a pair of oppositely acting pistons having a common working space, 15 the pistons of the two cylinders being cross connected and driving a common crank shaft.

According to this invention the oppositely situated pistons of the two cylinders are 20 cross connected by a pair of diagonal links and the two pistons at one end only of the engine are connected to the opposite ends of a rocking lever. The crank shaft is driven by a connecting rod from one of the 25 cross or diagonal links connecting the pistons, the connecting rod being attached to the link at about the middle of the latter.

In order that the said invention may be clearly understood and readily carried into 30 effect, the same will now be described more fully with reference to the accompanying drawings, in which:—

Figure 1 is a sectional elevation with parts removed and Figure 2 is a plan of an engine embodying this invention.

Figure 3 is a sectional elevation at right angles to Figure 1; and

Figures 4, 5 and 6 show constructional modifications of the engine.

40 All the figures are diagrammatic and show only such elements of the engine as are required to illustrate the invention.

A, A are the cylinders. B is the engine framing. C, C¹ are the pistons, four of which are employed, one pair C, C¹ being provided in each cylinder A. D is the driving diagonal link made in twin form for balance and symmetry and connecting the upper piston C¹ in one cylinder with the lower piston C in the second cylinder. E is the second connecting diagonal link, also in two members crossing the link member D at the outside, as shown in Figure 3, and connecting the remaining two pistons C, C¹ together. F is the crank shaft driven

through the connecting rod G from the driving link D. H is the rocking lever connecting together pistons C or C¹ at the same end of the cylinders.

Referring to Figures 1, 2 and 3, the link members D and E are rigidly secured at their ends to heads or brackets c, c¹ on the pistons C, C¹, the driving link D lying inside the connecting link members E and carrying the connecting rod pin d which secures the two link members D together at the middle and receives the upper end of the connecting rod.

The heads or brackets c of the upper cylinders C carry pins c² to which are attached the short links h connecting the pistons C to the opposite ends of the lever H. The links are secured on the lever pins h¹ and the lever rocks upon the trunnion pin h² carried in the bearing b in the top casting of the engine frame B. The diagonal links D and E travel in straight paths as they are directly connected to the ends of the pistons, but to take the side thrusts due to the drive the connecting rod pin d may be provided with the crosshead d¹ sliding between vertical guides b¹ forming part of the engine frame and comprising in the arrangement shown a set of steel bars of rectangular section passing from the top casting carrying the rocking lever to the lower part of the frame. The pistons during the outward portion of the strokes are guided in the cylinder extensions A¹ deeply slotted at a to allow of the passage of the heads or brackets c, c¹ and the associated pins, but the greater part of the side thrust may be taken by the guides b¹.

Instead of connecting the pistons to the lever H by links h the connection may be of the pin and slot type shown in Figure 4, in which the lever pin h³ is connected to a sliding block h⁴ sliding in a transverse slot c³ in the piston head c⁴, which is guided by means of the guides b² on the upper part of the engine frame B, the inner face of the head c⁴ sliding upon the guides b².

In the modification shown in Figure 5 the rocking lever H is placed at the bottom of the engine immediately above the crank shaft, the pistons C to which the lever is attached being in this case the lower pistons. Otherwise the arrangement is similar to that shown in Figures 1, 2 and 3.

In Figure 6 the rocking lever end of the

driving link D^1 is not connected direct to the piston head or bracket c but is attached to the pin of the lever H so that the end of the link moves in a small arc, the connection to the piston being through the lever link h . To allow for the slight angular movement of the upper part of the link D^1 it is made in two arms jointed at the connecting rod pin d , the connecting rod cross-head d^1 taking the side thrusts due to the crank shaft drive.

With a construction according to this invention a very compact and well balanced engine is obtained, in which the secondary or side stresses are reduced to a minimum, the heavy driving and connecting members moving as nearly as possible in a straight path, such side stresses as are due to the drive through the connecting rod being taken by the frame of the engine at a point where rigid support is readily provided.

What I claim and desire to secure for Letters Patent of the United States is:—

1. In a reciprocating engine, a pair of

parallel cylinders, a pair of oppositely acting pistons in each cylinder, a rocking lever at one end only of the cylinders, connected to the two pistons at that end, a pair of diagonal links cross connecting the oppositely situated pistons of the two cylinders, a crank shaft and a connecting rod from one of the said diagonal links to the crank shaft.

2. In a reciprocating engine, a pair of parallel cylinders, a pair of oppositely acting pistons in each cylinder, a rocking lever at one end only of the cylinders, short links connecting the ends of the said lever to the two adjacent pistons, a pair of diagonal links cross connecting the oppositely situated pistons of the two cylinders and rigidly connected to the pistons at the end opposite to the rocking lever, a crank shaft and a connecting rod from one of the said diagonal links to the crank shaft.

3. In an engine as claimed in claim 1, a crosshead on the inner end of the connecting rod and fixed guides for the crosshead.

JAMES McKECHNIE.
